COMPOSITION PANEL CABINET ASSEMBLY
PARTICULARLY ADAPTED FOR USE IN
MOLDED RADIO CABINETSKnut Eskid Birger Stenberg, Attleboro, Mass.,
assignor to Associated Attleboro Manufacturers,
Inc., Attleboro, Mass., a corporation of Massa-
chusetts

Application March 11, 1937, Serial No. 130,364

2 Claims. (Cl. 312—7)

My invention relates to improvements in cabinet assemblies and is particularly adapted for use in the manufacture of radio cabinets constructed of molded composition plastic material, such as synthetic resin, of the phenol formaldehyde condensation product type, urea formaldehyde condensation product, or other type, or other types of cellulose products, etc.

While it has been possible to mold small radio cabinets in one piece, the dies therefor have been extremely expensive and my invention relates to a cabinet assembly which will permit the use of much smaller dies than formerly thought possible and consequent reduction of expense in the molding apparatus.

A further disadvantage of integrally molded cabinets has been that they have had a sameness of design and a further feature of my invention is to provide an assembly comprising molded panels having edges which may be slid into interfitting engagement to make up the cabinet assembly and in which if desired respective panels of different color or design theme may be selectively substituted, thus permitting by variations in color or design of a small part of the cabinet many variations in the composite cabinet assembly color or design.

A further feature of my invention is to provide a cabinet assembly of the type hitherto described which may be retained in assembled position by the radio chassis or other base normally employed therewith to hold the desired operating parts in the cabinet.

A further object of my invention is to provide a cabinet assembly in which the edges of the various panels which slide into interfitting engagement are provided with suitable interfitting tongue and groove means to positively prevent leakage of gaseous material, such as impurities from the outside air to within or leakage of heat to without.

These and such other objects of my invention as may hereinafter appear will be best understood from a description of the accompanying drawings, which illustrate my invention applied to a standard type of relatively small sized radio cabinet assembly.

In the drawings, Fig. 1 is a front elevation of a radio cabinet assembly constructed in accordance with my invention containing the usual radio chassis base and the assembled radio parts therein.

Fig. 2 is a plan view of the cabinet assembly shown in Fig. 1.

Fig. 3 is a reverse plan view of the cabinet as-

sembly with the radio chassis base and operating parts removed.

Fig. 4 is a disassembled front elevation of the improved cabinet assembly shown in Figs. 1-3 showing from top to bottom the rear panel removed, the combination U-shaped top and end panels integrally joined together and the front panel removed.

Fig. 5 is a horizontal sectional view taken just above the chassis base along the line 5—5 of Fig. 1, showing the cabinet assembly in assembled position.

Fig. 6 is a vertical sectional view taken along the line 6—6 of Fig. 5.

In the drawings, wherein like characters of reference indicate like parts throughout, 10 generally indicates a cabinet assembly constructed in accordance with my invention, which comprises in its broadest sense a molded composition top panel 12, molded composition end panels 14^a and 14^b, a molded composition rear panel 16 and a molded composition front panel 18, (said panels 16 and 18 being referred to generally as side panels), certain of said panels preferably having their respectively adjacent edges integrally molded together, such as the top edges of the end panels 14^a and 14^b and end edges of the top panel 12 to form the integrally molded U-shaped composite top and side panel 20 and other of said respectively adjacent edges, in the embodiment shown, the end and top edges of the front and rear panels 16 and 18 and the front and rear edges of the top panel 12 and end panels 14^a and 14^b having molded interfitting tongue and groove means for slidably securing said panels together, whereby at least one of said panels may be replaced in the assembly by another of a different color or design theme. To retain the slidable panels together, at least some of said panels are provided with the lugs projecting inwardly at a spaced distance from the lower ends thereof, in the preferred embodiment said panels having lugs including the end panels 14^a and 14^b and the front and rear panels 16 and 18. To secure the panels in assembled relationship, a suitable base 24 is provided adapted to be confined within the lower ends of said side and end panels, (said side panels comprising said front and rear panels 16 and 18) to abut said lugs from underneath to secure said removable panels in assembled relationship.

In the particular embodiment shown, my improved cabinet assembly is preferably constructed in the following manner. While all of the panels heretofore described may be provided with in-

terfittng tongue and groove means for securing them together, I have shown in the drawings a construction wherein the top and end panels comprise an integrally molded composition 5 5 U-shaped composite panel 20 comprising the top panel 12 having the top ends of the end panels 14^a and 14^b integrally molded to the end edges thereof in a composite die. While the interfittng molded tongue and groove means may 10 be reversed on the edges of the panels described, in the preferred embodiment shown, I provide said composite panel member 20 with the aligned molded grooves 26 spaced substantially adjacent the front and rear edges thereof, thus extending 15 at each front and rear edge of the end panels 14^a and 14^b and the front and rear edges of the top panel 12 and to form interfittng means each end and top edge of the rear and front panels 16 and 18 respectively, (the side panels as hitherto 20 described) are provided with molded tongues 28 projecting therefrom adapted to project within said grooves, in the embodiment shown, said tongues being inset from the outer surfaces 30 of said front and rear panels. The grooves 26 25 may be constructed as shown by providing projecting ribs from the panel surfaces to form the grooves 28 in between them or they may be molded in the panel walls if the walls be made thick enough. The end panels 14^a and 14^b are 30 preferably tapered upwardly as are the end edges of the side panels, namely, the front and rear panels 16 and 18, not only to add to the appearance, but also to permit easier and quicker removal and assembly of the slidble front and 35 rear and other panels. In the embodiment shown all of said panels are provided with lugs, or other means substantially equidistantly spaced from the lower ends thereof, at least some of said lugs having screw holes for detachable 40 seurement of the chassis base 24 thereto to retain said panels in the assembled relationship. Thus, in the embodiment shown, for this purpose the rear panel 16 is provided with the spaced lateral lugs 32, the front panel is provided with the 45 integral lugs 34 also equidistantly spaced from the lower end thereof, and in the embodiment shown, located adjacent the inner surface of each end edge thereof and the end panels 14^a and 14^b are also provided with the lugs 36 also 50 equidistantly spaced from the lower ends thereof. In this instance, however, said lugs 36 are extended upwardly in the form of integrally molded ribs 36 transversely spaced from each other and having screw holes 38 in their lower 55 ends thereof for receiving screws 40 insertable through suitable screw holes 42 in the chassis base 24 within said screw holes 38 in said lugs so that said chassis base 24 may abut the respective lugs 32, 34 and 36 on the respective side panels 60 including the front panel 18 and the rear panel 16 and the end panels 14^a and 14^b, to positively shove the removable front and rear panels 16 and 18 upwards with the tongues 28 positively fitting and interlocking within the grooves 26 so 65 that when the screws 40 are completely screwed within said screw holes 38, all the panels will be held in rigid assembled position by the chassis base 24.

In the embodiment shown, the front panel 18 70 is provided with an enlarged dial and speaker hole 44 therein and also preferably has radio insignia, such as the wave length numbers 62 integrally molded in the front thereof around said hole 44 and said front panel 18 is provided with 75 the supplemental dial holes 48 therein. The en-

larged hole 44 is not only adapted to function as a loud speaker hole, but as a dial hole and to hold the loud speaker cloth in position adjacent said hole, it is preferably provided with the rearwardly projecting speaker cloth receiving lugs 60 5 projecting integrally inwardly therefrom adjacent the edge of the speaker hole 44. In addition, for radio purposes, other of said panels are provided with suitable air cooling holes therein and thus in the embodiment shown the upper panel 10 12 is provided with the vertically spaced air cooling slots 50 and the rear channel 16 is provided with the vertically spaced air cooling slots 52 which may be made of such a size as to permit the fingers to be inserted through said holes for 15 lifting said cabinet.

I have shown in Fig. 1 the exterior of a cabinet assembly constructed in accordance with my invention having a radio assembled therein and thus displaying through the hole 44 the speaker cloth 54 and showing the tuning dial 56 rotatably mounted centrally of said hole 44 and showing the tuning knobs 58 mounted on extensions from the radio parts projecting forwardly through said holes 48, it being obvious that the other necessary radio parts, such as the tubes, etc. may be readily mounted on the radio chassis 24.

In the drawings, I have shown the composite molded composition panel member 20 pigmented 30 red and the front, top and rear panel members 16 and 18 white. It is apparent that any of the panel members may be of any desired color and if it be desired to change the color, or design theme, it is merely necessary to replace a panel. 35 If desired a large number of the individual panel members of different colors may be made up from stock to be assembled in the desired color or design assembly on individual order.

While I have shown a three-piece assembly, 40 it is obvious that if desired the top panel may be made separately from the end panels to provide a five-piece structure, the interfittng portions or panels being provided if desired with the interfittng tongue and groove means characteristic of 45 my invention, or if desired similarly may be a four-piece structure constructed in accordance with my invention.

It is apparent therefore, that I have provided a novel type of cabinet assembly constructed of 50 molded composition material and particularly adapted for use in radio cabinets with the advantages explained above.

It is understood that my invention is not limited to the specific embodiments shown and that 55 various deviations may be made therefrom without departing from the spirit and scope of the appended claims.

What I claim is:

1. A radio cabinet assembly, comprising molded 60 composition integral U-shaped top and end panels having aligned molded grooves at the front and rear edges of said top and end panels and front and rear panels having tongues at the top and end edges thereof, whereby said front and rear panels may be assembled by sliding said tongues upwardly in said grooves, the removable front and rear panels having lugs substantially vertically equidistantly spaced from the lower ends thereof and the end panels having lugs substantially 65 equidistantly spaced from the lower ends thereof having screw holes for detachable seurement of a chassis base thereto insertable from underneath, whereby on seurement of said chassis base thereto, said chassis base may 70

abut the lugs on the removable front and rear panels to retain said front and rear panels with said U-shaped panel in assembled relationship, said front panel having an enlarged dial and speaker hole therein and speaker cloth receiving lugs integrally projecting inwardly adjacent the edge of said speaker hole.

2. A radio cabinet assembly, comprising molded composition integral U-shaped top and end panels having aligned molded grooves at the front and rear edges of said top and end panels, and front and rear panels having tongues at the top and end edges thereof, whereby said front and rear panels may be assembled by sliding said

tongues upwardly in said grooves, the removable front and rear panels having lugs substantially vertically equidistantly spaced from the lower ends thereof and the end panels having lugs substantially equally equidistantly spaced from the lower ends thereof having screw holes for detachable securement of a chassis base thereto insertable from underneath, whereby on securement of a chassis base thereto, said chassis base may abut the lugs on the removable front and rear panels to retain said front and rear panels with said U-shaped panel in assembled relationship. 5 10

KNUT ESKID BIRGER STENBERG.
